DESIGN FOR A DRESS

Herbert M. Harris, New York, N. Y.

Application March 22, 1939, Serial No. 83,741

Term of patent 3½ years

To all whom it may concern:

Be it known that I, Herbert M. Harris, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific two piece dress disclosed of the front button opening blouse section having curved yokes extending from either side of the square neckline in association with the specific inverted box pleats extending from the front yokes to the bottom and the specific contrastingly colored collar and cuffs as shown.

I claim:

The ornamental design for a dress, substantially as shown and described.

HERBERT M. HARRIS.
